UNITED STATES PATENT OFFICE

91,742

DESIGN FOR A BOTTLE PACKAGE

Adolf Tarr, Westfield, N. J.

Application January 18, 1934, Serial No. 50,440

Term of patent 7 years

To all whom it may concern:

Be it known that I, ADOLF TARR, am a citizen of the United States, residing at 133 Stanmore Place, Westfield, in the county of Union and State of New Jersey, have invented a new, original, and ornamental Design for a Bottle Package, as shown in the accompanying drawing and described in the following specification.

In the drawing:

Figures 1 and 2 are respectively front and side views of the package; and

Figure 3 is a plan view.

I claim:

The ornamental design for a bottle package as shown and described.

ADOLF TARR
